CLAIM

The ornamental design for a vanity mirror, as shown and described.

DESCRIPTION

FIG. 1 is a top, front, left-side perspective view of a vanity mirror embodying our design in a first state;
FIG. 2 is a top, rear, right-side perspective view thereof;
FIG. 3 is a front elevation view thereof;
FIG. 4 is a rear elevation view thereof;
FIG. 5 is a right-side elevation view thereof;
FIG. 6 is a left-side elevation view thereof;
FIG. 7 is a top plan view thereof; and
FIG. 8 is a bottom plan view thereof.

FIG. 9 is a top, front, left-side perspective view of the vanity mirror embodying our design in a second state;
FIG. 10 is a top, rear, right-side perspective view thereof;
FIG. 11 is a front elevation view thereof;
FIG. 12 is a rear elevation view thereof;
FIG. 13 is a right-side elevation view thereof;
FIG. 14 is a left-side elevation view thereof;
FIG. 15 is a top plan view thereof; and,
FIG. 16 is a bottom plan view thereof.

All features in broken line form no part of the claimed subject matter.

1 Claim, 12 Drawing Sheets
